(57) **CLAIM**

(21) Appl. No.: **29/146,659**

The ornamental design for a compressor for air conditioners of vehicles, as shown and described above.

(22) Filed: **Aug. 15, 2001**

DESCRIPTION

(30) **Foreign Application Priority Data**

Feb. 19, 2001 (JP) 2001-008580

FIG. 1 is a front view of a compressor for air conditioners of vehicles, according to the design.

(51) LOC (7) Cl. **15-02**

FIG. 2 is a rear view of the compressor, as shown in FIG. 1. FIG. 3 is a right side view of the compressor, as shown in FIG. 1.

(52) U.S. Cl. **D15/9**

FIG. 4 is a left side view of the compressor, as shown in FIG. 1.

(58) Field of Search D15/7-9; D23/325,

FIG. 5 is a top view of the compressor, as shown in FIG. 1.

D23/354; 418/63, 259

FIG. 6 is a front perspective view of the compressor of FIG. 1; and,

D356,862 S 3/1995 Ito et al.

FIG. 7 is a rear perspective view of the compressor of FIG. 1.

D381,340 S 7/1997 Takenaka et al.

It being understood that the broken lines are for illustrative purposes only.

D381,993 S * 8/1997 Takenaka et al. D15/9
